3 SHEETS--SHEET 3.

UNITED STATES PATENT OFFICE.

CHARLES M. LEECH, OF LIMA, OHIO.

ENGINE-STARTER.

1,091,519.

Specification of Letters Patent. Patented Mar. 31, 1914.

Application filed August 27, 1912. Serial No. 717,323.

To all whom it may concern:

Be it known that I, CHARLES M. LEECH, a citizen of the United States, residing at Lima, in the county of Allen and State of Ohio, have invented certain new and useful Improvements in Engine-Starters, of which the following is a specification.

The present invention relates to pneumatic means for cranking or starting an internal combustion engine.

An important object of the invention is to provide means of the above mentioned character, which are automatic in operation, simple in construction, durable, and cheap to manufacture.

A further object of the invention is to provide means of the above mentioned character, so constructed that when the same is at rest, it will not interfere with the proper operation of the engine.

In the practice of my invention I provide a device which is adapted to supply compressed air or the like to one side of the piston, to move the same in one direction. When the piston starts on its opposite movement, the device is automatically operated to cut off the supply of compressed air and exhaust the compressed air which has previously moved the piston.

In the accompanying drawings forming a part of this specification and in which like numerals are employed to designate like parts throughout the same, Figure 1 is a central vertical sectional view through an engine equipped with my improved structure, Fig. 2 is a central vertical sectional view through the device, showing the sliding valve in its intermediate position to establish communication between the interior of the crank case and the atmosphere, Fig. 3 is a similar view, showing the sliding valve in its uppermost position, to supply compressed air into the crank case, and, Fig. 4 is a similar view, showing the sliding valve in its lowermost position, the device being at rest and serving as means for allowing the free passage of air into or out of the crank case.

In the drawings wherein, for the purpose of illustration, I have shown a preferred embodiment of my invention, the numeral 5 designates an explosion cylinder of an internal combustion engine, provided with inlet and exhaust ports 6 and 7. Mounted to reciprocate within the cylinder 5 is a hollow piston 8, provided at its lower end with an

auxiliary piston 9, of greater diameter than the cylinder 5, as shown. The auxiliary piston 9 operates within a lower casing 10, connected with the cylinder 5 at its upper end 60 and with a closed crank case 11 at its lower end. Extending into the piston 8 is a pitman 12, connected therewith by means of a pin 13. The pitman 12 is connected at its lower end with a crank 14 by a pin 15. This 65 crank is rigidly connected with the crank shaft 16, as is customary. As no claim is made to the construction of the engine *per se*, it is thought that the above description will suffice.

The crank case 11 is provided with an opening 17, to receive a lower enlarged portion 18 of a shell included in my improved starter. The shell comprises an upper contracted portion 19, which is preferably cast 75 integral with the large portion 18. The contracted portion 19 extends downwardly within the large portion 18, as shown at 20.

Mounted to reciprocate within the contracted portion 19 is a sliding valve 21, provided with an opening or recess 22, as shown. The sliding valve 21 is connected with a stem 23, extending through an opening in the upper end of the contracted portion 19. A compressible coil spring 24 surrounds the stem 23 within the contracted portion 19 of the shell and serves to force the sliding valve 21 downwardly. Connected with the upper end of the stem 23 is a roller 25, which is adapted to engage a 85 cam 27, rigidly mounted upon the crank shaft 16.

Formed through the large portion 18 of the shell is an auxiliary exhaust port 28, which leads into the interior of the contracted portion 19, as shown at 29. A transverse port 30 serves to establish communication between the interior of the crank case and the interior of the portion 20 of the shell. Formed through the large portion 100 18 of the shell is a breathing port 31, having communication with an opening 32. The sliding valve 21 is provided near its upper end with a transverse port 33, which is adapted to be moved into registration with 105 the opening 32 only when the sliding valve 21 is in its lowermost position, as shown in Fig. 4. A pipe 33' leads into the breathing port 31.

The numeral 34 designates a pressure 110 storage tank, containing compressed air or the like. Connected with this tank is a pipe

35, which is connected with the lower end of the large portion 18 of the shell, as shown, to supply compressed air into the interior of the portion 20. Connected in 5 the pipe 35 is a valve structure including a shell 36 and a swinging valve 37 mounted therein. This valve is turned by a handle 38. The valve 37 is provided with a main transverse opening 39, which is adapted to 10 be moved into registration with the opening of the pipe 35, whereby the compressed air is supplied to the starter. The valve 37 is also provided with a small opening 40, leading into the main opening 39. The shell 15 36 is provided with a small opening 41, disposed at a right angle to main openings 42.

Attention is called to the fact that the 20 starter disposed to one side of the crank 14, so that it does not in any way interfere 25 with the operation of the engine.

The operation of the device is as follows:—When the valve 37 is closed, as shown in Fig. 4, the spring 24 moves the 25 sliding valve 21 to its lowermost position. The interior of the crank case 11 is now in free communication with the pipe 33', whereby air passes freely into and out of said 30 crank case during the movement of the piston. In the ordinary multiple cylinder engine the pipe 33' serves to couple all the 35 crank cases together, whereby they are in communication during the operation of the engine. I place one of my starting apparatuses within each crank-case, the same having suitable connection with the common 40 pressure supply pipe 35, above the valve structure 36. It is thought that as these starting apparatuses are identical only one need be shown and described in this application. Attention is called to the fact that 45 any compressed air contained within the pipe 35 above the valve 37 is free to exhaust to the atmosphere through openings 40, 39 and 41. The engine may now be considered 50 at rest. To start the same, the handle 38 is swung to move the valve 37 to its open position. Compressed air passes through the pipe 35 and forces the sliding valve 21 upwardly, to assume the position shown in 55 Fig. 3. The compressed air now passes through the port 30 into the crank case and forces the piston upwardly. When the piston reaches its uppermost position the cam 27 has been turned so that its large portion 55 engages the wheel 25 to force the valve 21 downwardly to assume its intermediate position, as shown in Fig. 2. The compressed air within the crank case 11 will now exhaust to the atmosphere through port 30, 60 opening 22, opening 29, and port 28. It is thus seen that the piston will be allowed to move downwardly. When the piston reaches its lowermost position, compressed air is again introduced into the crank case 65 to force the same upwardly. The operation

is thus automatically repeated until the valve 37 is closed, subsequently to which the spring 24 will move the sliding valve 21 to its lowermost position, as shown in Fig. 4. When the valve 21 is in its lowermost position, the interior of the crank case 11 is in free communication with pipe 33' through ports 30, 22, 33 and 31, whereby the interior of the crank-case will be placed in communication with the atmosphere or in breathing 70 communication with the other crank-case or crank-cases. 75

It is to be understood that the form of my invention herewith shown and described is to be taken as a preferred example of the 80 same and that certain changes in the shape, size, and arrangement of parts may be resorted to without departing from the spirit of the invention or the scope of the subjoined claims. 85

Having thus described my invention, I claim:—

1. The combination with an internal combustion engine comprising a cylinder, a piston operating therein, a closed crank case, a 90 crank shaft, and a pitman connecting the piston and crank shaft, of means to supply compressed air into the crank case to move said piston in one direction, and means automatically operated by the movement of the 95 piston to cut off the supply of compressed air from the crank case and establish communication between the interior of the same and the atmosphere, so that the piston may move in a reverse direction. 100

2. The combination with the closed crank case of an internal combustion engine, of means for supplying compressed air into the same, and means operated by such compressed air to establish communication between the interior of the crank case and the atmosphere. 105

3. The combination with the closed crank case of an internal combustion engine, of means for supplying compressed air into 110 the same for starting the engine, and automatically operated means to cut off the supply of compressed air from the crank case and place the interior of the crank case in communication with the atmosphere. 115

4. The combination with an internal combustion engine comprising a cylinder, a piston, a closed crank case, a crank shaft, and a pitman, of a device to start said engine, comprising a shell provided with an inlet 120 port leading into the crank case, and an exhaust port leading to the atmosphere, a sliding valve mounted within the shell and provided with an opening adapted when the valve is in a certain position to establish 125 communication between the inlet and exhaust ports, a spring to move the sliding valve in one direction, means operated by the crank shaft of the engine to move the sliding valve, and means to supply com- 130

pressed air into the shell to move the sliding valve in opposition to the spring.

5. The combination with an internal combustion engine comprising a cylinder, a piston, a closed crank case, a crank shaft, and a pitman, of a device to start the engine comprising, a shell having a breathing port, an inlet port leading into the crank case, and an exhaust port leading to the atmosphere, a sliding valve mounted within said shell and provided with transverse and longitudinal openings, a spring to move the valve in one direction, means for supplying compressed air into the shell to move the valve in a reverse direction, and means operated by the crank shaft of the engine to move said valve.

6. The combination with an internal combustion engine comprising a cylinder, a closed crank case connected with the lower end thereof, a crank shaft mounted within the crank case, a piston mounted within the cylinder and a pitman connecting the piston and crank shaft; of a device mounted within the closed crank case upon one side of the crank shaft and adapted to supply compressed air into the crank case upon the up stroke of the piston and cut off the supply of compressed air from the crank case and establish communication between the same and the atmosphere upon the down stroke of the piston; and a device mounted upon the crank shaft to automatically operate the device.

7. The combination with an internal combustion engine comprising a cylinder and piston operating therein, of a starting device to supply compressed air within the cylinder to move the piston in one direction and to alternately establish communication between the interior of the cylinder and the atmosphere, comprising a shell provided with inlet and exhaust ports, a sliding valve mounted within the shell and adapted to be moved to a position for connecting the inlet and exhaust ports and to another position for disconnecting them and uncovering the inlet port, a spring to move the sliding valve in one direction, and a pressure supply pipe leading into the shell near one end of the sliding valve to supply pressure therein to move the valve in opposition to the spring.

8. The combination with the crank-case of an internal combustion engine, of apparatus disposed near the crank-case to start the engine by compressed air or other fluid, comprising a shell provided with a breathing port, an exhaust port, and a pressure inlet port, and means whereby the ports are selectively placed in communication with the interior of the crank-case.

In testimony whereof I affix my signature in presence of two witnesses.
